ATTORNEY

UNITED STATES PATENT OFFICE.

GABRIEL BALAS, OF IZIEUX, FRANCE.

DESIGN FOR BRAIDING-CORD.

SPECIFICATION forming part of Design No. 24,218, dated April 16, 1895.

Application filed March 11, 1895. Serial No. 541,364. Term of patent 14 years.

To all whom it may concern:

Be it known that I, GABRIEL BALAS, a citizen of the Republic of France, residing at Izieux, near St. Chamond, in the Department of the Loire, France, have invented and produced a new and original Design for Binding Cords or Braids, of which the following is a specification.

In the drawings, forming part of this specification—Figure 1 is a plan view; and Fig. 2 an end elevation of my design.

The essential feature of my design consists in the substantial quadrangular disposition or shape of the braid.

At 1 in the drawings is an inner core of braid substantially square, and at 2 is an

outer covering for the same, the exterior lines of which form substantially a quadrangular figure, so as to present a square appearance. From one of the vertical sides of the braid or part 2, and at right angles thereto, extends a flat braided band 3.

I claim—

The design for binding cords or braids, substantially as herein shown and described.

Signed at Izieux, in the Department of the Loire and Republic of France, on the 11th day of February, 1895.

GABRIEL BALAS.
